UNITED STATES PATENT OFFICE.

CHARLES GILBERT HAWLEY, OF CHICAGO, ILLINOIS, ASSIGNOR TO CENTRIFIX CORPORATION, OF CLEVELAND, OHIO, A CORPORATION OF OHIO.

TANK FILTER.

Application filed May 4, 1925. Serial No. 27,858.

My invention relates to means for purifying water as it leaves the tank or reservoir containing it. As will presently appear the device or fixture embodying my invention may be employed in the purification of liquids generally under such conditions and further, may be combined with the stop valve which controls the flow of the liquid.

The invention will be readily understood on reference to the accompanying drawing; in which Fig. 1 is a vertical section of a centrifugal fixture comprising a water purifier embodying my invention, on the line 1—1 of Fig. 2; Fig. 2 is a vertical section on the line 2—2 of Fig. 1; Fig. 3 is a horizontal section on the line 3—3 of Fig. 1; Fig. 4 is a section on the line 4—4 of Fig. 1; Fig. 5 illustrates the application of the invention to a locomotive tender; and Fig. 6 its application to a railway water tank or tower.

In Figs. 1 and 2 the plate 2 represents the bottom of the liquid tank. That bottom contains a large hole 3. The kettle-shaped casting or forging 4 hangs from the floor 2 and presents an open top 4' which registers with the hole 3. Preferably the means of attachment comprises the integral flange 4'' at the top of the pot or casing 4.

Near the top is a circumferential internal flange 4^a which serves as the seat for the wide flange 5 of the stop valve 6. The stop valve shown is the form usually employed in locomotive tender tanks, and occupies its usual position, being operated by means of the vertical stem 6'. The valve flange 5 is attached to the casing and made tight by a packing and a number of bolts 5'.

Midway between the top and bottom of the kettle 4 is a second and wider circumferential flange 4^b preferably containing a shoulder or seat 4^c. It also contains the large central opening 4^d. Both the shoulder 4^c and the opening 4^d are coaxial with the stop valve 6. The part 4^e is an integral elbow formed within the bottom of the kettle and externally extended to provide the nipple 4^f to which the flexible hose 7 (see Fig. 6) is attached. The upper end of the elbow portion 4^e contains a central opening 4^g which is considerably smaller than the opening 4^d. The upper end of the elbow terminates in the circumferential flange 4^h which is also of greater diameter than the opening 4^d. By preference, the top of the flange is characterized by the circumferential shoulder 4ⁱ and the downwardly

pitched or beveled marginal part 4^j. The top of the elbow flange 4^h stands considerably below the under side of the flange 4^b thereby leaving the circumferential space 4^k which opens directly into the top of the cavity 8 surrounding the elbow 4^e. The member 9 comprising, the bottom ring 9^a, the tuyère blades 9^b, and the closed top 9^c constitutes a multiple tangential tuyère; through which the descending liquid must pass to reach the open elbow 4^e. The complete circumferential series of tangential blades 9^b appears in Fig. 3 which also discloses the many tangential tuyères 9^d. The tuyère or tuyère ring 9 is seated in the shoulder 4^c and is held by two or more clamping bolts 9^e. It is of low height and large diameter, yet its tuyères 9^d have an aggregate area exceeding that of the valve 6, also that of the nipple 4^f.

It is to be noted that the bottom of the elbow 4^e stands above the bottom of the kettle or casing 4. Thus space is provided for the short valve casing 4^m having two ports 4ⁿ which open into the space or cavity 8. The casing 4^m is bored to receive the tapered valve plug 10, having ports 10' that can be turned to register with the ports 4ⁿ. This small valve is preferably coaxial with the stop valve 6, is set at substantially right angles thereto and is connected therewith by a short stem 10'', to turn with the stop valve. As shown the stem extends through a hole provided in the top 9^c of the tuyère 9.

The stop valve, as is usual on tender tanks, is opened and closed by means of a lever 6''. The arrangement is such that when the stop valve is completely open the small plug valve 10 is closed; and when the stop valve 6 is nearly shut the plug valve 10 is open, and obviously, remains open so long as the stop valve 6 is completely closed. This relation of the valves may of course be varied to suit the judgment of the locomotive designer.

Upon the opening of the stop valve 6 the water rushes downward over and around the tuyère 9, and through that, to the outlet 4^g and discharge elbow 4e. The tangential tuyères through which the water must pass divide the stream into many relatively thin streams or films which must move in a direction transverse to the longitudinal axis of the tuyère. The result of this is that the heavier substances, generally termed solids, carried by the water are instantly projected or impacted against the inner sides of the tuyère 11.

blades, and further, all of the water occupying the tuyère, the circumferential space or gap 4^k and the top of the outlet 4e is set into rapid rotation. It follows that the initially separated solids are held in a separated state by centrifugal force and upon reaching the circumferential gap 4^k are centrifugally projected against the wall of the casing beneath the flange 4^b, thence to sink into the cavity 8 through the relatively quiet body of water occupying it. Thus, the solids are centrifugally extracted from the flowing stream by energy derived from its fall and are deposited in the cavity 8, leaving the clarified liquid to escape through the outlet or elbow 4^e. From the latter the water is conducted to the injector or pump of the locomotive which drives it into the locomotive boiler. The great advantages in boiler operation and boiler maintenance will at once be apparent to those skilled in the art.

During the operation of the locomotive the stop valve lever 6^{''} is occasionally worked to open the plug valve 10 and discharge the accumulated solids onto the track. If this intermittent operation of the stop valve is objected to, a separate valve lever may be applied to the sludge valve 10. But the danger is that an independent valve lever will be neglected and the sludge valve left open and result in emptying the tank.

When applied to larger tanks, as in the case represented in Fig. 6, the purifier is of greater size and the main stop valve 11 may be arranged in connection with the discharge spout 12. Further, the kettle or casing 4^x may be deeper to provide a large sludge cavity, and it may have an independently operated sludge valve 10^x.

Lest it be thought that the proportions and the shape illustrated in Figs. 1 and 2 are not important, attention is called to the necessity

of making the fixture as small as possible in height and with a bottom that shall afford adequate clearance between the fixture and the wheeled truck which carries the front end of the tender.

Having thus described my invention I claim as new and desire to secure by Letters Patent:—

1. The herein described liquid purifier, comprising a bowl-like casing which is open at the top and the lower part of which contains a centrally positioned stand-pipe serving as the outlet for the purified liquid, in combination with means at the top of said casing for attaching it to the bottom of a liquid tank, a whirl-promoting tuyère centrally positioned in said casing and operatively interposed between the upper and lower parts of said casing, and also positioned above the upper end of said stand-pipe, means closing the top of said casing, a stop valve positioned thereon and means for emptying the sludge from the bottom of said casing.

2. The herein described liquid purifier, comprising a bowl-like casing which is open at the top and the lower part of which contains a centrally positioned stand-pipe serving as the outlet for the purified liquid, in combination with means at the top of said casing for attaching it to the bottom of a liquid tank, a whirl-promoting tuyère centrally positioned in said casing and operatively interposed between the upper and lower parts of said casing, and also positioned above the upper end of said stand-pipe, means closing the top of said casing, and means for emptying the sludge from the bottom of said casing.

In testimony whereof I have hereunto set my hand this 30th day of April, A. D. 1925.

CHARLES GILBERT HAWLEY.
